UNITED STATES PATENT OFFICE.

REUEL T. MARKEE, OF PHILADELPHIA, PENNSYLVANIA.

HEAT-CONSERVING APPARATUS.

1,016,346.

Specification of Letters Patent.

Patented Feb. 6, 1912.

Application filed June 4, 1909. Serial No. 500,132.

To all whom it may concern:

Be it known that I, REUEL T. MARKEE, a citizen of the United States, and a resident of the city and county of Philadelphia, 5 State of Pennsylvania, have invented certain new and useful Improvements in Heat-Conserving Apparatus, of which the following is a full, clear, and complete disclosure.

This invention relates to that class of receptacles which are provided with an inner chamber insulated from its surroundings in such a way that the temperature of the same is conserved and kept substantially constant for a long period of time. They 10 may, therefore, be used to keep hot articles hot and likewise, to keep cold articles cold. Among such receptacles are included fireless cookers, refrigerators, including refrigerator cars, coolers, vacuum cans and the 15 like.

This invention more particularly relates to that species of receptacles enumerated in which a vacuum is mainly relied upon to form the heat insulating medium.

20 Among the improvements which are hereinafter described may be mentioned the use of a lining of material such as porcelain for the inner chamber and the surrounding of the vacuum chamber by a dead air space. 25 There are various other improvements disclosed herein, such as in the valve of the vacuum chamber and the means for sealing the same, the manner of strengthening the walls of the device and insulating the same 30 from each other, and the manner of keeping the cover on the inner chamber.

Further improvements involved in this invention, will be carefully pointed out in the following description and specifically 40 referred to in the appended claims.

In the drawings Figure 1 is a vertical section through a vacuum receptacle showing one embodiment of this invention; Fig. 45 2 is a horizontal cross section on the line 2—2 of Fig. 1; Fig. 3 is a plan view of the same with the cover partly broken away; Fig. 4 is a plan view of a refrigerator showing another embodiment of this invention; Fig. 5 is a horizontal cross section through 50 the same; Fig. 6 is a view partly in front elevation and partly in vertical section of the same; Fig. 7 is a horizontal section through the wall of a large refrigerator such as a refrigerator car or building.

The vacuum can 1, shown in Figs. 1, 2 55 and 3 consists of a double walled inner receptacle 2 and a container 3, completely enclosing the receptacle 1.

The receptacle 2 comprises an inner wall 4, having a bottom portion 5 and a side 60 portion 6 and an outer wall 7, having a bottom portion 8 and a side portion 9 parallel respectively to the bottom portion 5 and the side portion 6 of the inner wall 4. The side portions 6 and 9 are joined air 65 tight in any suitable manner. In the present instance, the side portion 6 is shown formed with an outwardly projecting perpendicular flange 10 at its upper end, which is connected to the end of the side portion 70 9 by soldering or welding.

In order to give greater stability to the inner wall 4, the side portion 6 thereof is extended at the bottom, as shown at 11 to meet the bottom portion 8 of the outer wall 75 7, thereby forming a rest for the inner wall. Adjacent to the point of contact of the extension 11 with the bottom 8 and on the inner side thereof, an annular rib 12 is struck up from the bottom to form a firm 80 support for the extension 11. The latter is also provided with perforations 13 in order not to interrupt the space between the inner wall 4 and the outer wall 7.

As the air is exhausted from the space 85 14 between the inner wall 4 and the outer wall 7, it has been found desirable to reinforce these walls. For this purpose the circumferential rib 15 is struck outwardly from the inner wall 4 and a similar rib 16 90 is struck inwardly from the outer wall 7. In addition to this, bosses 17 may be struck up at various points from these walls and project beyond the ribs 15 and 16. These bosses may be struck up on the line of the 95 ribs as shown, or at other places. They are arranged to register with each other and a washer 18 of asbestos or like heat insulating material, may be inserted between their ends. The washers 18 are concave on both 100 sides to form seats for firmly engaging the ends of the bosses 17. It will thus be seen that a simple and efficient means is provided for preventing the walls of the vacuum chamber from collapsing.

For the purpose of permitting the air to be exhausted from the space 14, a valve 22 is provided in any suitable portion of the

inner wall 4, or outer wall 7. In the present embodiment the valve is located in the bottom portion 8 of the outer wall 7. A hole 23 is provided in the bottom 8 and over this 5 hole is placed a cup-shaped device or boss 24 forming a valve chamber 25. The boss 24 may be made separate from the bottom 8 and secured thereto in any well known manner, as shown at the top of Fig. 1, or it may be 10 made integral with the same, as shown at the bottom of Fig. 1. At its inner end, it is provided with a hole 26 closed by the ball 27. Various means may be used for permanently closing the valve 22 after the 15 air is exhausted from the space 14. In the present instance there is shown a plate 30 arranged to slide on the bottom 8, in guides 31. The plate 30 is provided with a hole 32 which registers with the hole 23 while the 20 air is being exhausted from the space 14. It is then moved so that the holes 32 and 23 are out of register with each other, and the plate is then attached to the bottom, as by soldering.

25 It has been found that there is a tendency for the bottom portions 5 and 8 to come together, both because of the weight of material in the interior of the receptacle pressing down on the bottom 5 and because of pressure applied upwardly on the bottom 8 when the vacuum chamber is being exhausted. These pressures are exerted in addition to the unbalanced pressure of the atmosphere which tends to press these portions together. 30 In order to obviate this difficulty, a ring 35 may be inserted around the valve 22, between the bottoms 5 and 8; this ring is provided with perforations 36 for providing communication with the remaining portion of the 35 vacuum space 14.

40 The receptacle 2 is provided with a cover or stopper 40 and a valve 42, similar except as noted above, to the valve 22. It also has a ring 43 similar to the ring 35, and bosses 45, for the purpose of reinforcing the same. It comprises a portion 46 which fits snugly within the side portion 6 at the top and a surrounding portion 47, which is seated upon the tops of the side portions 6 and 9, whereby 50 by an air tight connection is formed between the stopper 40 and the receptacle 2.

55 For the purpose of still further insulating the receptacle 2, it is provided with a lining 44 of refractory material, such as porcelain. This lining is particularly desirable in this connection as it forms a smooth unbroken surface for the receptacle and covers over the indentations formed by the ribs and bosses.

60 The receptacle 2 is wholly enveloped by the container 3. This container is provided with a rib 55 and bosses 50 on its bottom and sides which are struck inwardly and serve to space the receptacle from the container 3,

and thus form a dead air space between the same. If desired, these bosses may be permanently secured to the outer wall of the inner receptacle as by soldering or gas or electric welding. A cover 51 is hinged at the top of the container 3 and is adapted to be locked into position by the locking lever 52 65 70 co-operating with the projection or catch 53. At the center of the cover 51 there is a downwardly extending boss 54 which bears against the stopper 40 when the cover 51 is in closed position and operates to bind the 75 stopper 40 tightly in closed position.

The refrigerator 60, shown in Figs. 4, 5 and 6, discloses another embodiment of this invention. It comprises a double wall inner receptacle 61, provided with a vacuum chamber 62, similar in construction to the vacuum can described above. Unlike the vacuum can, it has two stoppers 63 and 64 on top, which are each similar in construction to the stopper 40 and the side door 65, which differs 80 85 from the stoppers, in that the outer wall 66 which surrounds the dead air chamber is attached to the walls forming the vacuum chamber. Another difference that will be noted is that the wall of the vacuum chamber 90 adjacent to the wall 66, is provided with bosses struck out on both sides, the inwardly extending bosses operating to reinforce the walls of the vacuum chamber, and the outwardly extending bosses serving to space the 95 wall of the vacuum chamber from the outer wall 66. The door 65 may be provided with an ordinary latch 67. It will also be noted that the continuity of the dead air space is interrupted at the side door and between the 100 stoppers 63 and 64. The top doors 68 and 69 of the container are provided with hinges 70, and hand holds 71.

105 The stopper 63 forms a closure for the ice chest 75, which is located in the upper corner of the refrigerator 60. The ice chest is provided with a spigot 76 and a drain pipe 77 having a water seal 78 to prevent the access of air to the ice chest.

110 The walls of the refrigerator have brackets 79 struck out from the same at suitable points to provide supports for shelves. It is obvious, however, that any other means might be used for supporting the shelves. A porcelain lining similar to that shown in 115 the vacuum can may also be used in the refrigerator.

Fig. 7 shows the application of my invention to a section of a wall of a refrigerator car or building. The vacuum chamber 120 80 is formed of two parallel walls 81 and 82, which are provided with strengthening ribs 83 and registering bosses 84. A heat insulating washer 85 is inserted between the adjacent ends of registering bosses. These 125 vacuum chambers are placed between the

supporting studs 86 which may be T-irons as shown, and are spaced from the outer wall 87 so that a dead air chamber may be formed between the vacuum chamber and the wall 87. The chambers 86 may also be insulated from the outer wall 87 by a layer of mineral wool, or similar material, as shown at 88, and wooden studs 89, may be inserted between the ends of the vacuum chambers and 10 the T-irons.

I preferably make my heat conserving apparatus out of sheet metal or similar material, but I may use different materials in the construction of certain of the parts, such as 15 wood in the outer wall, at the same time retaining the essential elements of this invention.

It will be understood that the invention disclosed herein is not limited to the precise 20 details of construction described, but many changes may be made therein without departing from the spirit and scope of the same.

Having thus described my invention, I 25 claim and desire to protect by Letters Patent of the United States:—

1. In an article of the class described, an inclosure forming a vacuum chamber having the walls thereof provided with inwardly 30 extending stiffening ribs and bosses projecting from said ribs and holding said walls spaced apart.

2. In an article of the class described, an inclosure forming a vacuum chamber having the walls thereof provided with inwardly 35 extending stiffening ribs, bosses projecting from said ribs and holding said walls spaced apart and heat insulating material inserted between the ends of said 40 bosses and the contacting portion of the opposite wall.

3. In an article of the class described, an inclosure forming a vacuum chamber having the walls thereof provided with inwardly 45 extending stiffening ribs, bosses projecting from said ribs and holding said walls spaced apart, and washers of heat insulating material concaved to fit on the ends of said bosses inserted between said ends and the contacting 50 part of the opposite wall.

4. In an article of the class described, an inclosure forming a vacuum chamber having the walls thereof provided with inwardly 55 extending stiffening ribs and registering bosses projecting from said ribs and holding said walls spaced apart.

5. In an article of the class described, an inclosure forming a vacuum chamber having the walls thereof provided with inwardly 60 extending stiffening ribs, registering bosses projecting from said ribs and holding said walls spaced apart and heat insulating washers having concaved surfaces to fit on

the ends of said bosses inserted between the ends of said registering bosses. 65

6. In a heat insulating receptacle a double walled receptacle, having the air exhausted from between the walls of the same, a double walled stopper hermetically sealing said receptacle, and a container surrounding said receptacle and spaced apart from the same, said container being provided with a cover having a substantially spherical boss for engaging and holding said stopper in position when said cover is closed, 70 said stopper and boss on said cover having a minimum degree of contact and said cover inclosing a dead air space adjacent to said stopper and surrounding said boss.

7. In a heat insulating receptacle, a double walled receptacle having the air exhausted from between the walls of the same, a double walled stopper hermetically sealing said receptacle, and a container surrounding said receptacle and spaced apart 85 from the same, said container being provided with a pivoted cover having a boss extending inwardly therefrom for engaging and holding said stopper in closed position when said cover is closed. 90

8. In a receptacle, an inner vessel and a container surrounding said inner vessel, said container being provided with inwardly projecting bosses for spacing apart said vessel and said container, and said bosses being permanently secured to said inner vessel. 95

9. In an article of the class described, an inclosure forming a vacuum chamber having its walls provided with a port and a bushing surrounding said port for holding the walls of said chamber apart. 100

10. In an article of the class described, an inclosure forming a vacuum chamber having parallel walls, one of said walls being provided with a port for exhausting said chamber and a ring located in said chamber surrounding said port and bracing said walls apart. 105

11. In an article of the class described, an inclosure forming a vacuum chamber having parallel walls, one of said walls being provided with a port for exhausting said chamber and a perforated ring located in said chamber surrounding said port, and bracing said walls apart. 110

12. A temperature conserving device comprising a receptacle provided with double walls inclosing a vacuum, a container surrounding said receptacle and forming a 120 dead air space around the same, and a lining of refractory material for said receptacle.

13. A temperature conserving device comprising a receptacle provided with double 125 walls inclosing a vacuum, an outer wall sur-

rounding said receptacle and forming a
dead air space around said receptacle, and a
closure for said device provided with a
vacuum chamber and an outer dead air
5 chamber, the walls of said dead air cham-
ber contacting, to prevent collapsing, at
spaced points only.

In witness whereof, I have hereunto set my
hand this 26th day of May, A. D., 1909.

REUEL T. MARKEE.
